FIG. 3

To all whom it may concern:

Be it known that I, Frank V. Gandola, a citizen of the United States, residing at Rocky River, county of Cuyahoga, and State of Ohio, have invented a new, original, and ornamental Design for a Combined Hand Truck and Wheelbarrow, of which the following is a specification, reference being had to the accompanying drawings, forming a part hereof.

Fig. 1 is a top view in perspective of a combined hand truck and wheelbarrow showing my new design with the lower crossbar shown in folded position;

Fig. 2 is a side view in perspective; and

Fig. 3 is another side view in perspective of the device

with the box portion removed and with the lower crossbar in operating position for use as a hand truck.

I claim:

The ornamental design for a combined hand truck and wheelbarrow, substantially as shown.
